CENTERING REINFORCING CONSTRUCTION FOR COLUMNS

Application filed December 28, 1926. Serial No. 157,570.

This invention relates to reenforcing for concrete, and the invention is particularly applicable in connection with the molding of concrete columns. These columns are usually provided with a circumferential re-enforcing member which is generally in the form of a helical coil of steel. It is customary to provide vertical bars to which some or all of the turns of the coil are attached. It is advantageous to construct the columns of hollow form.

The general object of this invention is to provide a reenforcing construction especially adapted for constructing a hollow column of concrete and which will insure the proper centering of the reenforcing coil with respect to the axis of the column; also to provide a saddle of simple construction which can be attached to vertical reenforcing bars in a column to facilitate centering them and the coil to which they are attached.

Further objects of the invention will appear hereinafter.

The invention consists in the novel parts and combination of parts to be described hereinafter, all of which contribute to produce an efficient centering reenforcing construction for columns.

A preferred embodiment of the invention is described in the following specification, while the broad scope of the invention is pointed out in the appended claims.

In the drawing:

Figure 1 is a side elevation showing a short portion of a column embodying my invention, the ends of the view being broken away.

Figure 2 is a horizontal cross section upon an enlarged scale, taken upon the line 2-2 of Fig. 1.

Figure 3 is a vertical section taken on the line 3-3 of Fig. 2.

Fig. 4 is a perspective of the device which I provide for insuring the proper centering of the reenforcing within the column.

Figure 5 is a plan of the blank for the body of the device shown in Fig. 4.

Figure 6 is a plan of the key which I employ for securing the device to the vertical reenforcing bars.

The invention may be practiced with any

form of circumferential reenforcing. In the present instance I have illustrated the circumferential reenforcing in the form of a coil 1 of reenforcing steel, and I have illustrated the column 2 as being of tapered form, but, if desired, the column may be of true cylindrical shape. In the present instance the reenforcing coil 1 is of gradually reduced diameter toward its upper end.

There is also provided a core 3 which is of conical form, and this core is set up with its axis coinciding with the axis of the column which is to be formed. The reenforcing coil 1 is disposed about the core 3 with its axis coinciding with that of the core.

In addition to the reenforcing coil 1, I provide a plurality of vertical reenforcing bars 4, and these bars are attached to the turns or loops of the coil 1. Any suitable means may be employed for that purpose. In the present instance this is accomplished by striking tongues 5 out of the material of the bar and bending the same over to form a hook 6 (see Fig. 3), which holds the coil against the outer side of the bar.

In order to center the coil with respect to the axis of the column, I provide a plurality of centering devices, such as illustrated in Fig. 4. This device is in the form of a saddle or saddle plate, that is to say, the body 7 of the saddle is in the form of a plate, the ends of which are bent on transverse lines in the plane of the flat side of the plate, and at right angles to the body of the plate to form extensions 8. These extensions operate as spacers to hold the bars 4 away from the side of the core 3. In Fig. 5 I illustrate the plate out of which the saddle is formed. This plate is provided with a long slot 9 which is so long that when the plate is bent to form the saddle, the ends of this slot extend out into the extensions 8, as indicated at 10 in Fig. 4. This slot is of tapered form and the material which is struck out from the slot forms a key 11 (see Fig. 6), which I employ in this slot to secure the saddle on its corresponding bar 4.

The reenforcing coil and the vertical bars 4 are preferably attached together before they are set up to form the column. After they

have been set up so as to encircle the core, I then apply the saddles in the manner indicated, that is to say, the saddle is applied so that the extensions 8 project toward the axis of the column with their ends unattached to, but lying against the side of the core. After the saddle is applied in this way, the key 11 is driven into the slot on the opposite side of the bar so as to secure the saddle to the bar. If the saddle plate is used on a bar where there is no circumferential reenforcing, that is to say, where there is no cross member attached to the vertical bar, the key 11 should be sprung slightly to one side so that it will operate to clamp the vertical bar resiliently and hold the saddle in place upon it. With a construction such as that described, having coils, it is not necessary that the key 11 should clamp the saddle on the bar for the reason that the saddle will be supported anyhow upon the nearest coil or loop of the coil, or more exactly upon the hook 6 which is formed over the loop of the coil just below the saddle.

I prefer to form the ends of the extensions 8 with a notch 12 which extends about half-way across the plate out of which the saddle is formed. This arrangement gives the plates sufficient strength and stability and at the same time enables me to form a greater number of saddle blanks from a metal bar of a given length. The notch 12 which is formed on one end of the plate is at the upper end, and the notch 12 at the other end is formed near the lower edge of the plate. This will form all of the saddles alike and enable the end of one saddle to be struck from the bar without any waste of material between them.

I claim:—

1. In a reenforcing construction for hollow columns and the like, the combination of a circumferentially disposed reenforcing member, a plurality of vertical reenforcing members connected with the circumferential member, a plurality of centering saddles mounted on the vertical members and having extensions projecting inwardly toward the axis of the column, and a core within the column unattached to the saddles abutting against the extensions and cooperating with the saddles to center the circumferential reenforcing member in the column.

2. In a reenforcing construction for columns, the combination of a helical member disposed around the axis of the column, a plurality of vertical bars attached to the coils of the helical member, a plurality of saddles consisting of bent plates respectively with their inner faces lying against the outer faces of the vertical bars, and having extensions projecting inwardly toward the axis of the column, means associated with each saddle for securing the same on its corresponding vertical bar, and a core disposed within the column engaging the ends of the extensions,

but unattached to the core and cooperating with the same to hold the helical member centered in the column.

3. A centering saddle for centering a circumferential reenforcing member in a column, consisting of a flat plate having a body bent on transverse lines in the plane of its flat face so as to form an extension at each end, said plate having a slot extending longitudinally in its body and extending into said extensions, and a transverse key to be received in the ends of said slot to secure the saddle to a bar held between the key and the body of the saddle.

4. As a new article of manufacture, a blank of a centering saddle for centering a circumferential reenforcing member in a column, said blank consisting of an elongated substantially rectangular plate with a tapered opening extending longitudinally throughout substantially the length of the same and having a notch extending into the same from one of its end edges adjacent one side of the blank and a notch extending into the same from the other end edge adjacent the other side of the blank.

Signed at Compton, Cal., this 22 day of December, 1926.
